UNITED STATES PATENT OFFICE.

EVERETT B. LANGENBERG, OF ST. LOUIS, MISSOURI, ASSIGNOR TO LANGENBERG
MANUFACTURING CO., OF ST. LOUIS, MISSOURI, A CORPORATION OF MISSOURI.

DESIGN FOR A DISPLAY STICKER.

Application filed December 7, 1928. Serial No. 29,153. Term of patent 14 years.

To all whom it may concern:

Be it known that I, EVERETT B. LANGENBERG, a citizen of the United States, residing in the city of St. Louis and State of Missouri, have invented a new, original, and ornamental Design for Display Sticker, substantially as shown in the accompanying drawing.

The drawing is a plan view showing the display side of my new design for display sticker.

I claim:

The ornamental design for display sticker, substantially as shown.

EVERETT B. LANGENBERG.
